VIBRATING SCREEN

Leon E. Chamberlain, Oakfield, N. Y., assignor to
Alfred E. Fielding, Buffalo, N. Y.

Application January 19, 1939, Serial No. 251,769

2 Claims. (Cl. 209—326)

This invention relates to improvements in vibrating screens, particularly those of the kind which, owing to the fine mesh of the screening cloth or the nature of the material to be screened, or both, have a tendency to blind.

The principal object of the invention is to provide a screen which is so designed that any tendency to blind, regardless of the cause, is counteracted, this object contemplating the association with the conventional actuating mechanism of means for imparting supplemental impulses to the screening cloth to clear the openings of material which might otherwise obstruct them.

A further object is to provide improvements of the character generally described which may be either incorporated in the screens as originally constructed or which may be applied to existing screens as an attachment.

A still further object is a screen wherein provision is made for varying the intensity of the impulses produced by the supplemental vibrating means.

A still further object is to provide a screen which is so constructed that the impulses of the supplemental vibrating means are transmitted substantially uniformly throughout the screening areas.

A still further object is to provide a novel design and arrangement of the parts of the screen, whereby simplicity and economy in construction are insured.

The invention is illustrated in the accompanying drawing in which:

Figure 1 is a side elevational view of a vibrating screen embodying the features of the invention. Figure 2 is an enlarged transverse vertical section taken along line 2—2 of Figure 1. Figure 3 is an enlarged fragmentary section taken along line 3—3 of Figure 2. Figure 4 is a detail view of one of the impulse producing elements of the supplemental vibrating means.

The features of the invention are illustrated, by way of example, in connection with a screen having a live frame 6 and a base frame 7, the former including side plates 8 and 9 between which upper and lower screening decks 10 and 11, respectively, are secured. The base frame 7 includes longitudinally extending members 12 which carry bearings 13. The latter provide a mounting for an actuating shaft 14 which passes through the side plates 8 and 9 substantially centrally of the live frame. Springs 15 which are located at opposite ends and on each side of the live frame act against the members 12 and 16 which are carried by the side plates 8

and 9 to maintain the live frame in the proper position and at the same time support a part of its weight. The actuating shaft 14 is enclosed in a tubular housing 17, it being understood that those portions of the said shaft upon which the live frame is mounted are, in accordance with conventional practice, eccentric with relation to those portions mounted in the bearings 13. Hence a rotary movement of the actuating shaft 14 will cause the live frame to move in a circular path, the entire movement of the live frame being in a vertical plane. During such movement of the live frame it is prevented from canting with respect to a predetermined normal position, whereby all portions of the live frame move in circular paths of substantially the same diameter. The actuating shaft is driven by a suitable motor (not shown) which may be mounted upon the base frame and connected by a suitable belt to one of the pulleys 18 formed or provided upon the opposite ends of the said shaft, the latter preferably also carrying flywheels 19 which are adapted to counterbalance the centrifugal forces set up during operation of the screen. So much of the screen as has been described is of conventional design and has, therefore, been illustrated only generally.

In accordance with the invention, means is provided for imparting supplemental vibrating impulses to the live frame 6 in order to clear the screening openings of material which might otherwise obstruct them. The said means includes angle bars 20 which are suitably secured to the undersides of the longitudinally extending base frame members 12. Each of the said angle bars, as illustrated, carries a plate 21 which in turn carries a bracket 22, the angle bars 20 and the horizontal portions of the brackets 22 being formed with aligned guide openings 23 for impact elements 24. The latter are mounted for axial movement. Compression springs 25, which are arranged around them, abut at their lower ends against the angle bars 20, while at their upper ends they abut against washers 26 applied to the respective impact elements below their guide brackets 22 and held against upward displacement by stop pins 27 applied to such elements.

The impact elements 24 are shown as cooperating with cross bars 29 of the live frame. The said cross bars are located at opposite sides of, and at substantially equal distances from, the actuating shaft while the impact elements are located directly under the cross bars at points substantially midway between the side plates of

the live frame. The impact elements are supported so that during movement of the live frame through the upper portion of its path of travel the cross bars 29 move out of contact with and away from them and permit them, under the influence of the springs 25, to move to the upper limits of their ranges of movement, while during movement of the live frame toward the lower portion of its path of travel the said cross bars strike the impact elements to impart supplemental vibrating impulses to the live frame. The springs 25 permit the impact elements to yield when they are struck in the manner described and during the remainder of the movement of the live frame through the lower portion of its path of travel. The impulses thus produced are sharp and are transmitted through the live frame to the screening decks. As they travel at right angles with respect to the said decks, they are particularly effective in clearing the screening openings. The intensity of the impulses is dependent, among other factors, upon the speed of the live frame, the weight of the impact elements and the compression of the springs 25. It may be varied, therefore, by varying the compression of the said springs. To this end each of the elements 24 is formed with a series of spaced holes or bores 30 (Figure 4) to provide for adjustment of the pins 27 to enable compression of the springs 25 to the desired degree.

From the foregoing it will be apparent that the arrangement of the impact elements in the manner described has the advantage that they counteract one another insofar as any tendency to rotate the live frame upon the actuating shaft is concerned. In this connection it is to be understood that the use of a single impact element on each side of the actuating shaft, as shown, is by way of illustration only and that the invention contemplates the employment of various numbers and arrangements of the said elements as circumstances may require.

I claim as my invention:

1. In a vibrating screen, a base frame, a screen frame resiliently mounted on said base frame,

means for positively gyrating said screen frame in a vertical plane, impact means disposed between said base frame and the bottom of the screen frame for imparting vibrations to the screen frame supplementary to those normally imparted thereto, said means including supporting bracket attached to said base frame below the screen frame and having vertical guide-ways therein, a vertically-displaceable impact bar engaging the bracket guide-ways for movement toward and from said screen frame and for abutting thrust engagement at its upper end with the adjoining portion of the screen frame, and a compression spring applied to said bar for yieldingly resisting its downward displacement and imparting smart up-thrusts thereto to supplement the normal vibrations of the screen frame, said impact bar being spaced from the screen frame during a part of its gyrating path and being engageable therewith during another part of such path.

2. In a vibrating screen, a base frame, a screen frame resiliently mounted on said base frame, means for positively gyrating said screen frame relative to said base frame through a fixed path lying in a vertical plane, and means for imparting supplemental vibrations to said screen frame comprising a bracket attached to said base frame below said screen frame, said bracket having substantially horizontally-disposed, upper and lower portions having aligned guide openings therein, an impact bar guided in said openings and extending at its upper end freely above the upper portion of said bracket for thrust engagement with the screen deck, and a compression spring coiled about said bar and abutting at its lower end against the lower portion of the bracket, the upper end of the spring abutting against a washer applied to the bar below the upper portion of said bracket, said means being so positioned that said screen frame is out of contact with said impact bar in the upper portion of said path, and strikes said impact bar during motion toward the lower portion of said path.

LEON E. CHAMBERLAIN.
